(57) **CLAIM**

The ornamental design for an anchor point for an air tool, as shown and described.

DESCRIPTION

FIG. 1 is a perspective view of an anchor point for an air tool showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a perspective view thereof attached to an air tool. The broken lines shown in the figures illustrate structures for illustrative purposes only and form no part of the claimed design.
